DESIGN FOR A BOTTLE

Charles P. Englehardt, New York, N. Y., assignor
to Oldetyme Distillers, Inc., New York, N. Y.,
a corporation of New Jersey

Application April 20, 1936, Serial No. 62,209

Term of patent 14 years

To all whom it may concern:

Be it known that I, Charles P. Englehardt, a citizen of the United States, residing at New York, in the county of Kings and State of New York, have invented a new, original, and ornamental Design for a Bottle, of which the following is a specification, reference being had to the accompanying drawing forming part thereof.

The figure is a perspective view of the bottle showing my new design as it appears when viewed

from a point approximately at the front right hand corner of the bottle. The rear face of the bottle is exactly the same as the front face which is shown and the left side is exactly the same as the right side of the face which is shown.

I claim:

The ornamental design for a bottle substantially as shown and described.

CHARLES P. ENGLEBARDT.
